UNITED STATES PATENT OFFICE.

ARNOLD NÜESCH, OF BASEL, SWITZERLAND.

DEVICE FOR ASSISTING CALVING IN CATTLE.

Application filed April 29, 1925, Serial No. 26,733, and in Switzerland May 17, 1924.

The invention relates to a device for assisting calving in cattle, that is an apparatus to facilitate normal labour in cattle with a double purpose, firstly for the better treatment of the animal and secondly to be able to apply the necessary pull without requiring two or more persons.

The ordinary means for assisting calving with a normal end position of the head consist in fastening cords to the front feet, when the labour itself does not suffice or appears to be about to suffice for dropping the calf. One or more persons pull on these cords. Apparatuses have been constructed so as to 15 increase the pull of these persons, which is frequently insufficient, by artificial means, which are constructed on the principle of toothed wheel gearing or compound pulleys.

The above mentioned manual pulling and 20 the hitherto known pulling apparatuses have, however, great faults, which are firstly that the pull is only applied to the feet so that the head may not come with them but may dip back behind the front knees, and so (unknowingly) an abnormal position is produced by the head and knee joints which makes calving difficult. Secondly both with 25 pulling by several persons and more particularly with inanimate machines, such as toothed winches and pulley devices, all the necessary judgment of the force to be applied is lacking and also every possibility of 30 technically correct operation as regards direction, quality and limitation of pulling. The direction of pulling is correct when it 35 has a slight downward slope, the quality of pulling when the traction is as far as possible in agreement with the labour, increasing slowly up to its greatest extent and also 40 slowly reducing, to repeat this in a similar way at each recurring effort of the cow; the limitation of the pulling is on the one hand keeping quantitatively the force applied within certain limits and on the other hand 45 keeping this force confined on the calf alone, for when, for example, four men pull on a calf the cow generally moves from where it is lying until it hangs on its halter chain or rope, the force used being thus very bad for 50 the animal because it is not confined solely to the calf.

The device for assisting calving according to the invention is designed with these considerations in view. It consists of a support 55 to form an abutment against the rump of the cow and a manually operated pulling

lever adjustably carried thereon, which is adapted to be attached to the front feet of the calf (or the hind feet in the reverse representation) and which enables the birth to 60 be assisted at given times and with the desired force by a modulated pull in correct co-operation with the labour of the cow.

The drawings show by way of example an embodiment of the invention. 65

Figure 1 shows it in use.

Figure 2 is a longitudinal section of the device and

Figure 3 is a plan view of the support.

A support A which is provided at one end 70 with a fork a adapted to abut against the rump of the cow, is furnished with cylindrical pins b spaced apart and adapted to receive a separate pulling lever D which may be hooked on one or other of said pins. The 75 lever D carries a sleeve or collar d adjustably fastened to it, to which latter, as seen in Figure 1, the cords c to be fastened to the front feet of the calf are attached, as well as cords g to which are attached eye hooks f of a design suitable for the anatomical conditions. 80

By means of this apparatus the person assisting the calving, who holds with one hand the support A against the rump of the cow and with the other hand operates the lever 85 D, can apply a uniform pull on the head and feet at the desired moment and with any desired variable force and thus can assist the ordinary labour of the cow itself in the most satisfactory way. In this way a single person is sufficient for operating the apparatus, 90 who can apply the necessary force by means of the lever D. By adjusting the sleeve d on the lever D which can be fixed thereon by a set screw i, the leverage can be altered as desired. 95

Further, as the apparatus abuts against the rump of the cow, the pull is only effected on the calf, whilst without the abutting support A the tension would be distributed to 100 the calf and the cow. This feature also considerably facilitates the calving.

The treatment of the animal is also improved in that there are not three or more men pulling, who never all pull and release again in the best possible direction and at the suitable moments, as is possible if the necessary force is applied by a single hand and the force used is made approximately the same as that exerted by the cow. 105

As regards the eye hooks f, they differ from those hitherto known in that they are 110

suited to the anatomical conditions as they abut against the lachrymal bone and, in the further operation, against the upper jaw bone and nose bone, so that the tension causes no inclination of the head and no injury to the calf. Their connection to the lever D ensures simultaneous pulling on the front feet and the head so that head obstruction causing difficult birth is avoided.

10. What I claim is:

1. A device for assisting calving in cattle, comprising a support arranged to form an abutment against the rump of the cow, a manually operated rocking lever mounted thereon, means to allow said lever to be transferred from one place to another on said support and pulling means connected to said lever and arranged to be attached to the extremities of the calf, so as to allow of assisting the labour by means of a modulated pull in correctly timed and measured cooperation therewith.

2. A device for assisting calving in cattle, comprising a support arranged to form an abutment against the rump of the cow, a manually operated rocking lever thereon, a plurality of spaced pins along said support, hooking means on said lever to allow same to be transferred from one to another of said pins, and pulling means connected to said lever and arranged to be attached to the extremities of the calf, so as to allow of assisting the labour by means of a modulated pull in correctly timed and measured cooperation therewith.

3. A device for assisting calving in cattle, comprising a support arranged to form an abutment against the rump of the cow, a manually operated rocking lever thereon, means to allow said lever to be transferred

from one place to another on said support, an adjustable member on said lever, pulling means connected to said adjustable member and arranged to be attached to the extremities of the calf, so as to allow of assisting the labour by means of a modulated pull in correctly timed and measured cooperation therewith.

4. A device for assisting calving in cattle, comprising a support arranged to form an abutment against the rump of the cow, a manually operated rocking lever thereon, means to allow said lever to be transferred from one place to another on said support and pulling means connected to said lever and arranged to be attached to the extremities of the calf, eye hooks and pulling means connected to said lever, so as to allow of assisting the labour by means of a modulated pull on both the extremities and the head in correctly timed and measured cooperation therewith.

5. A device for assisting calving in cattle, comprising a support arranged to form an abutment against the rump of the cow, a manually operated rocking lever thereon, means to allow said lever to be transferred from one place to another on said support, an adjustable member on said lever, pulling means connected to said adjustable member and arranged to be attached to the extremities of the calf, eye hooks and pulling means also connected to said adjustable member, so as to allow of assisting the labour by means of a modulated pull on both the extremities and the head in correctly timed and measured cooperation therewith.

In witness whereof I have hereunto signed my name this 16th day of April, 1925.

ARNOLD NÜESCH
